UNITED STATES PATENT OFFICE

WALDO SHELDON, OF SOUTH NORWALK, CONNECTICUT

HOISTING APPARATUS

Application filed May 5, 1926. Serial No. 106,849.

This invention relates to the drilling of oil wells.

Special objects of the invention are to utilize the best features of rotary drilling methods, combined with the advantages of pressure feed and to effect this with relatively simple, powerful, readily transportable apparatus, constructed so that it may be handled substantially as a single unit.

10 Other special objects of the invention are to combine the different units of the apparatus in a compact, well balanced structure with the several parts located for their most handy and efficient control and operation, to provide full accessibility for care or removal of the different portions of the apparatus, to provide full flexibility and variable speed control particularly of the rotary table and hoist mechanism, and in general, to provide a 15 machine of this nature which will be practical in every way for the purposes intended.

The many novel features of construction, combinations and relations of parts by which the foregoing and other objects are attained 20 will appear as the specification proceeds.

In the drawings forming part of this specification and to which attention is now invited, some of the numerous possible embodiments of the invention are illustrated and it is to be 25 understood that other structural modifications and changes may be made without departure from the broad spirit and scope of the invention as hereinafter defined and claimed.

Figure 1 is a side elevation of the machine 30 as mounted on parallel beams laid on the transverse beams of a steel derrick floor.

Figure 2 is substantially a plan view of the same with the intermediate hoist mechanism removed.

40 Figure 3 is a broken plan part sectional view showing a modified form of two speed drum and cat head drive and with a selective speed gear box substituted in place of the motor in Figure 2.

45 Figure 4 is a cross sectional view as on substantially the plane of line 4-4 of Figure 2 of another modification showing the high speed and low speed clutches in section and sprocket chain drive from these clutches to 50 the drum.

Figure 5 is a similar view of the first form of the invention, Figures 1 and 2, showing spur gear drive between the clutches and drum and showing internal speed reducing gearing in the drum.

55 Figure 6 is a view of the right hand end of the machine shown in Figures 1 and 2.

One of the special features of the invention is the mounting of the various units of the machine, all on a sled like base or frame, made 60 up of two side sills 1 connected at intervals by cross braces 2. These sills and cross braces may be I-beams, the cross braces of less depth than the sills (Figure 5), the lower flanges of the sills serving as flat runners and being 65 shown as turned up at the ends at 3 after the manner of sled runners.

The motor or transmission gearing is mounted on one end of the frame, the rotary 70 table is mounted on the opposite end, the hoist is positioned intermediate the two and the hoist and table are driven by line shafting extending from the motor or transmission gearing at one end of the frame, beneath the hoist, to the rotary table at the opposite 75 end.

The motor shown at 4 in Figures 1 and 2 is an especially compact rotary cylinder steam engine, but it will be understood that internal combustion or electric power may 80 be used in place of the power unit shown. This motor is shown as having outstanding support lugs 5 which may rest upon and be bolted direct to the side sills as in Figure 2, or be mounted on step blocks 6 which in turn 85 are bolted on the side sills as shown in Figure 1.

Where the apparatus is to be driven from another or outside power source, a set of transmission gearing may be substituted in 90 place of the motor as indicated in Figure 3 where 7 designates a change speed gear box having lateral supports 8 by which it is bolted on the sills in place of the motor.

Extending from the motor, Figures 1 and 2, or from the gear box, Figure 3, is the line shafting 9 located substantially centrally of the frame in suitable bearings 10 mounted on the cross braces. Interposed in this shafting 100 are shown, in the order named, a chain uni-

versal coupling 11, a main clutch 12 controlled by lever 13, a coupling 14, a rotary table clutch 15 controlled by lever 16 and a coupling 17. The rotary clutch being interposed between the two couplings 14, 17 makes it possible to remove this clutch when necessary without disturbing other parts.

The rotary table is indicated at 18 and is shown as driven by a bevel pinion 19 on the 10 end of the shaft engaging a bevel gear ring 20 on the under side of the table.

The support for the table is shown as a relatively massive flat and substantially square base plate 21 secured by bolts 22 on top 15 of the frame at the end opposite the motor or transmission gearing and carrying a dependent sleeve 23 to serve as a long rigid bearing for the table.

The drill pipe is shown in the main view at 20 28 gripped by a special clamp 29 carried by a sleeve 30 which is slidingly keyed in the table at 31. This drive sleeve is raised and lowered to lift the drill pipe or to impart feeding movement thereto by power mechanism 25 shown as an annular cylinder 32 concentrically hung to the lower end of the bearing sleeve by a clamp structure 33 and containing an annular piston having an upwardly projecting annular piston rod for imparting the 30 lifting and lowering thrust to the drive sleeve.

The power fluid which may be water under pressure is shown as admitted to the upper and lower ends of the power cylinder through 35 piping 38, 39 under control of a special valve 40.

The hoist mechanism consists of a drum 41 journaled on a shaft 42 which is supported in side frames 43 mounted on the sills intermediate the opposite ends of the main frame. To drive this drum at different speeds, a low speed and a high speed clutch are provided 40 driven from the main shaft and connected to the drum by suitable gearing.

The low speed and high speed clutches are indicated respectively at 44, 45 in Figures 2, 4 and 5, the low speed clutch in Figure 4 being indicated as of the positive jaw type having interengaging driving and driven jaws 46, 47 and the high speed clutch being shown 50 as of the frictional type having engaging clutch plates 48. The teeth of the jaw clutch are shown as having inclined faces 49 adapted to ride over each other to positively disengage this clutch when the high speed friction 55 clutch takes hold.

These clutches are shown mounted on shafts 50 supported at their inner ends in sockets 51 in the sides of the main shaft bearing 52 and 60 rigidly secured at their outer ends by set screws 53 in brackets 54. This construction enables either one of the clutches being dropped by simply withdrawing the shaft 50 which supports it.

65 The difference in speed of the two clutches

is obtained as shown in Figure 2 by driving the low speed clutch by a relatively large bevel gear 55 in mesh with a bevel pinion 56 on the main shaft and the high speed clutch by a smaller bevel gear 57 in mesh with a bevel pinion 58 on the main shaft. It will be noted that the drive pinions 56, 58 are on opposite sides of the main shaft bearing 52 so as to engage the clutch gears 55, 57 at opposite sides of their centers. In this way both 75 clutches are driven in the same direction.

The means for operating the low speed and high speed clutches respectively are shown as foot pedals 59, 60, Figure 2, the first operating a shaft 61 carrying an arm 62 engaged with the forked end 63 of a lever 64 pivoted at 65 and having its opposite forked end 66 engaged with a movably shifting collar 67 of said clutch. The high speed clutch pedal 60 operates a sleeve 68 loose on shaft 61 and carrying a lever arm 69 connected by link 70 with the clutch shifting lever 71 which is pivoted at 72 and engages the shift collar of the high speed clutch at 73.

Different forms of gearing may be employed for effecting the drive of the drum from the two different speed clutches. Thus in Figures 1, 2 and 5, the driven members of the clutches are shown as carrying surrounding spur gears 74, 75 for engagement, the first, 95 with a ring gear 76 carried by a member 77 rotatable on the drum shaft and the second (75) engaging a ring gear 78 directly attached to the drum.

In Figure 4 the driven element of the first 100 or low speed clutch is shown as carrying a sprocket pinion 79 over which passes a sprocket chain 80 engaging a sprocket gear 81 on the rotatable gear element 77 and the driven element of the second or high speed clutch 105 is shown as carrying a sprocket pinion 82 over which passes a chain 83 engaging a sprocket gear 84 directly attached to the rim of the drum.

The drum shown in Figures 1, 4 and 5 is 110 of an internal gearing type having a shaft 85 journaled eccentrically therein, carrying a pinion 86 on one end meshing with a pinion 87 fixed on the sleeve 88 of the rotatable member 77 and carrying a pinion 89 on its opposite end engaging a gear ring 90 carried by a member 91 rotatably supported on the opposite end of the drum shaft. The outer surfaces of the rotatable gear carrying members 77 and 91 are shown finished as brake rings 92, 93 engageable by brake bands 94, 95 so that either or both said members may be held stationary. These brake bands are indicated in Figure 1 as anchored to a cross bar 96 secured between the side frames 43 and as having their free ends equipped with links 97 pivoted at 98 to rocker arms 99. One of these rocker arms is fixed on shaft 100 which is operated by a hand lever 101 and the other is fixed on a sleeve 102 rotatable on shaft 100 and actu-

ated by hand lever 103. Thus, by means of hand lever 101, the brake 94 may be set to hold the gear ring 76 and by means of hand lever 103 brake 95 may be set to hold the gear ring 90.

In the latter instance, with gear ring 90 held stationary and the low speed clutch engaged, the gear 76 will be rotated by the low speed clutch gear 74, causing the inside pinion 87 to drive pinion 86 of the drum shaft 85 which in its rotation causes pinion 89 to ride over the fixedly held gear 90 and hence "walk" the drum around said last gear at relatively slow speed. When the brake drum 93 is to be held for a continuous period, a lock pin or dog 104, Figure 5, may be inserted through the adjacent side frame into a seat 105 in the body of the drum. The brake levers may be counterweighted as indicated at 106, Figure 1, so that they will normally stand with brakes released.

For high speed operation of the hoist shown in Figure 5 the high speed clutch 45 is engaged and this being directly geared to the drum through the spur gearing 75, 78 or the sprocket gearing shown in Figure 4, drives the drum at the desired high speed.

The drum is shown in Figures 4 and 5 as having integral brake rings 107 at opposite ends of the spool adapted to be acted on by brake bands 108 suitably operated as by means of linkage and hand lever similar to those described.

The cat head drive is shown in Figure 5 as taken off the low speed ring gear 76 by means of a pinion 109 on the cat head shaft 110. This shaft is journaled on top of the side frames and carries the cat heads 111 at opposite ends and a positive jaw clutch is shown at 112 for coupling the pinion 109 to this shaft. For operating the cat heads this clutch 112 is engaged, the drum is held stationary by the center brakes 108 and the dogging pin 104 being withdrawn and brake 95 released, the low speed clutch 44 is thrown in so that the cat heads will be operated without turning the drum. The cat heads may be secured when not in use by movable pawls 113 engageable with ratchets 114 at the inner sides of the cat heads.

The hoist shown in Figure 3 is generally similar to that described, except that the internal gears are omitted and the drum is driven at low or high speed by ring gears 115, 116 directly attached to the drum and engaged with the low speed and high speed clutch gears 74, 75 respectively. In this form of construction the brake rings 107 for the drum are located at the ends of the spool. This form of hoist can thus be operated either at low speed or at high speed by directly engaging the low speed, or high speed clutches, which being directly geared to the drum operate the same accordingly.

The speed change gear box 7 shown in Fig-

ure 3 provides possibility for further speed changes, the same being operated by a hand lever 117 connected with a gear shifting shaft 118 entering the gear box and serving to shift the gears in the usual way. Power is applied to the entering end of the gear box by shafting 119 shown as carrying a sprocket gear 120 driven by sprocket chain 121 from a suitable source of power.

The cat head drive in Figure 3 is taken from the main shaft by a sprocket gear 122 on said shaft connecting by chain 123 with sprocket gear 124 on shaft 125 journaled in a bearing bracket 126 on top of one of the side frames and carrying bevel gear 127 in mesh with a bevel gear 128 on the cat head shaft 110.

With the form of hoist shown in Figure 3, when only the cat head drive is to be used, the main clutch 12 may be thrown out so that only the cat heads will be driven. This structure has the further advantages of a variety of different drum speeds because in addition to the so-called high and low speed drives attainable from the high and low speed clutches, other speeds may be had by utilizing the different gear sets in the change speed gear box. If desired, this gear box may contain a set of reverse gears so that the hoist may be reversed without reversing the motor. This is particularly desirable where the power is supplied by an internal combustion engine. Where steam or electric power is used the reverse drive is effected by reversing the motor.

The variety of controls provided in this invention enable all the usual and special rotary drilling operations being readily performed, with or without the use of the power feed as well as of the usual and special hoisting operations to be effected both by the hoist drum and the cat heads. The hoist is capable of both fast and slow operation and the two speed clutches enable the change from high to low or from low to high to be quickly effected without injury or shock to the mechanism.

The various controls are usually located as indicated in Figure 1 adjacent the hoist and in position where the driller can readily observe both the operation of the rotary and the action of the hoist and cat heads. This view shows also how the controls for the engine, indicated at 129, 130 may be brought forwardly from the engine to a position adjacent the other controls. Thus, without moving from this intermediate station the driller may start, stop and reverse the motor, may control the hoist and cat head operation, the operation of the rotary table and the action of the power feed mechanism.

The arrangement of the motor at one end of the frame, the hoist intermediate and the rotary table and power feed at the opposite end, provides a close couple compact and well balanced structure enabling a short drive

shaft from the motor to the hoist and table and provides also a structure which may be readily transported and fits in with the modern derrick structure. Any time that it may be necessary to move the apparatus, the same may be shifted by the usual skidding operations after the power cylinder and rotary have been unbolted and blocked up on the frame so that they clear the bottom line of the runners or skids. The apparatus may be set crosswise directly on the cross beams 131 of the derrick floor or, if desired, be mounted on parallel longitudinal beams 132 placed on the cross beams and spaced the same as the side sills of the frame. The latter may be preferred because of the ease with which the device may be skidded into place. The apparatus may then be bolted in place by inverted U-strips engaged over the side sills and bolted at their lower ends to the beams of the derrick floor.

For high speed operation of the drum, such as for repairing the empty block or for lifting out a light line of pipe, the drum may be driven directly from the cat head shaft by providing a gear on that shaft in mesh with the gear on the drum and clutch means such as an ordinary jaw clutch operable to couple this extra gear to the cat head shaft, it being understood that when this drive from the cat head shaft is being used, both the lower drum drive clutches will be disengaged.

What is claimed is:

1. Well drilling apparatus comprising line shafting carrying oppositely faced bevel gears, bevel gears of different diameters driven at different speeds but in the same direction by said first named gears, different speed clutches operated by the driven bevel gears, hoist mechanism, gearing connecting said clutches with said hoist mechanism and means for arbitrarily controlling the different speed clutches.

2. Well drilling apparatus comprising line shafting carrying oppositely faced bevel gears, bevel gears of different diameters driven at different speeds but in the same direction by said first named gears, different speed clutches operated by the driven bevel gears, hoist mechanism, gearing connecting said clutches with said hoist mechanism and means for arbitrarily controlling the different speed clutches, the low speed clutch being of the positive jaw type with beveled faces to permit overrunning of the clutch members and the high speed clutch being of the frictional type.

3. In well drilling apparatus, a hoist drum, a drive shaft, bevel pinions arranged in opposed spaced relation on said drive shaft, bevel gears of different sizes engaged with said pinions and driven thereby in the same direction but at different speeds and gearing from said different speed bevel gears

to the drum, including independently operable clutches.

4. In well drilling apparatus, a hoisting drum, a drive shaft beneath said drum and extending at a right angle to the axis thereof, bevel pinions spaced in opposed relation on said shaft, bevel gears of different size driven by said pinions and mounted beneath the drum with their axes in line and parallel to the drum axis and gearing from said different size gears to the drum including independently operable clutches beneath the drum on the same axes with the different size bevel gears.

5. In well drilling apparatus, hoist mechanism, a drive shaft, bevel pinions in spaced opposed relation on said shaft, bevel gears of different sizes driven by said pinions in the same direction but at different speeds and independently controllable gearing from said different speed gears respectively to the hoist mechanism.

6. In apparatus of the character disclosed, a drive shaft, sections of shafting disposed at right angles thereto, clutches mounted on said sections, gearing for driving said clutches from the drive shaft in the same direction but at different speeds and hoist mechanism operated by said different speed clutches.

7. In apparatus of the character disclosed, a drive shaft, a bearing therefor, supporting shafts at right angles to said drive shaft and supported by the opposite sides of said bearing, clutches on said side shafts, gearing for driving said clutches from the drive shaft at different speeds and hoist mechanism operable from said clutches.

8. In apparatus of the character disclosed, a drive shaft, a main bearing through which the drive shaft extends, supporting seats at opposite sides of said main bearing, supporting brackets in line with said seats, shaft sections rigidly held in said brackets and supported at their inner ends by the seats of the main bearing, gears on said side shafts, hoist mechanism operated by said gears, opposed bevel gears on the drive shaft at opposite sides of the main bearing and bevel gears on the side shafts and in mesh with the bevel gears on the drive shaft.

9. In apparatus of the character disclosed, a drive shaft, a main bearing through which the drive shaft extends, supporting seats at opposite sides of said main bearing, supporting brackets in line with said seats, shaft sections rigidly held in said brackets and supported at their inner ends by the seats of the main bearing, gears on said side shafts, hoist mechanism operated by said gears, opposed bevel gears on the drive shaft at opposite sides of the main bearing, bevel gears on the side shafts and in mesh with the bevel gears on the drive shaft and independently controlled clutches on the side shafts providing

couplings between the bevel gears and hoist driving gears thereon.

10. In apparatus of the character disclosed, a drive shaft, a main bearing through which the drive shaft extends, supporting seats at opposite sides of said main bearing, supporting brackets in line with said seats, shaft sections rigidly held in said brackets and supported at their inner ends by the seats of the main bearing, gears on said side shafts, hoist mechanism operated by said gears, opposed bevel gears on the drive shaft at opposite sides of the main bearing, bevel gears on the side shafts and in mesh with the bevel gears on the drive shaft and independently controlled clutches on the side shafts providing couplings between the bevel gears and hoist driving gears thereon, said supporting shafts being withdrawable through the outer securing brackets to enable said clutches being dropped between said brackets and the seats of the main bearing.

11. In apparatus of the character disclosed, a hoisting drum having two sets of gears for operating the same and means for driving said sets of gears at different speeds comprising line shafting and two sets of bevel gears of different speed ratios interposed between the line shafting and drum gears and including spaced bevel pinions on the line shafting faced toward each other and bevel gears faced toward each other but on opposite sides of the line shafting in the space between the pinions on the shafting.

12. In apparatus of the character disclosed, a hoisting drum having two sets of gears for operating the same and means for driving said sets of gears at different speeds comprising line shafting and two sets of bevel gears of different speed ratios interposed between the line shafting and drum gears and including spaced bevel pinions on the line shafting faced toward each other and bevel gears faced toward each other but on opposite sides of the line shafting in the space between the pinions on the shafting, shafting supporting said bevel gears at opposite sides of the line shafting and the sets of gearing for operating the drum, including large spur gears on the drum and spur pinions meshing therewith and mounted on the side shafting in driven relation to the bevel gears.

13. In apparatus of the character disclosed, a hoisting drum having two sets of gears for operating the same and means for driving said sets of gears at different speeds comprising line shafting and two sets of bevel gears of different speed ratios interposed between the line shafting and drum gears and including spaced bevel pinions on the line shafting faced toward each other and bevel gears faced toward each other but on opposite sides of the line shafting in the space between the pinions on the shafting, shafting supporting said bevel gears at oppo-

site sides of the line shafting and the sets of gearing for operating the drum, including large spur gears on the drum, spur pinions meshing therewith and mounted on the side shafting in driven relation to the bevel gears and clutch mechanism for independently controlling the driving relation between the bevel gears and drum driving pinions.

14. In apparatus of the character disclosed, a drive shaft, cross shafts at opposite sides of said drive shaft and angularly related thereto, bevel pinions on the drive shaft faced toward each other and disposed at opposite sides of the axes of the cross shafts, a hoisting drum over the cross shafts, bevel gears supported by the cross shafts each in engagement with one of the bevel pinions on the drive shaft and drive gearing for operating the drum from either of the bevel gears on the cross shafts.

15. In apparatus of the character disclosed, a drive shaft, cross shafts at opposite sides of said drive shaft and angularly related thereto, bevel pinions on the drive shaft faced toward each other and disposed at opposite sides of the axes of the cross shafts, a hoisting drum over the cross shafts, bevel gears supported by the cross shafts each in engagement with one of the bevel pinions on the drive shaft and drive gearing for operating the drum from either of the bevel gears on the cross shafts and including independently operable clutches on the cross shafts.

16. In apparatus of the character disclosed, a drive shaft, cross shafts at opposite sides of said drive shaft and angularly related thereto, bevel pinions on the drive shaft faced toward each other and disposed at opposite sides of the axes of the cross shafts, a hoisting drum over the cross shafts, bevel gears supported by the cross shafts each in engagement with one of the bevel pinions on the drive shaft and drive gearing for operating the drum from either of the bevel gears on the cross shafts and including independently operable clutches on the cross shafts, one of said clutches being of the frictional type and the other being of the positive jaw type with the jaws arranged for overrunning engagement.

17. In apparatus of the character disclosed, a drive shaft, cross shafts at opposite sides of said drive shaft and angularly related thereto, bevel pinions on the drive shaft faced toward each other and disposed at opposite sides of the axes of the cross shafts, a hoisting drum over the cross shafts, gears carried by the heads of said hoisting drum, bevel gears supported by the cross shafts each in engagement with one of the bevel pinions on the drive shaft and drive gearing for operating the drum from either of the bevel gears on the cross shafts and including independently operable clutches on

the cross shafts, and gears operated by said clutches in mesh with the gears at the heads of the hoisting drum.

18. In combination, a hoisting drum, a shaft journaled eccentrically in said drum and extending between the heads of said drum, pinions on the ends of said shaft, a drive pinion concentrically related to the drum and in mesh with the pinion on one end of the shaft aforesaid, a ring gear concentrically related to the drum and engaged by the pinion on the opposite end of said shaft, a brake for holding said ring gear and means for driving the drum independently of the gearing described and including a gear surrounding the ring gear but directly connected with the adjacent head of the drum.

19. In combination, a hoisting drum, a shaft journaled eccentrically in said drum and extending between the heads of said drum, pinions on the ends of said shaft, a drive pinion concentrically related to the drum and in mesh with the pinion on one end of the shaft aforesaid, a ring gear concentrically related to the drum and engaged by the pinion on the opposite end of said shaft, a brake for holding said ring gear, means for driving the drum independently of the gearing described and including a gear surrounding the ring gear but directly connected with the adjacent head of the drum and means for operating the concentric drive pinion, including a gear concentrically related to the opposite head of the drum.

20. In combination, a hoisting drum, a shaft journaled eccentrically in said drum and extending between the heads of said drum, pinions on the ends of said shaft, a drive pinion concentrically related to the drum and in mesh with the pinion on one end of the shaft aforesaid, a ring gear concentrically related to the drum and engaged by the pinion on the opposite end of said shaft, a brake for holding said ring gear, means for driving the drum independently of the gearing described and including a gear surrounding the ring gear but directly connected with the adjacent head of the drum, means for operating the concentric drive pinion, including a gear concentrically related to the opposite head of the drum and a brake for said last mentioned gear.

21. In combination, a hoisting drum, a shaft journaled eccentrically in said drum and extending between the heads of said drum, pinions on the ends of said shaft, a drive pinion concentrically related to the drum and in mesh with the pinion on one end of the shaft aforesaid, a ring gear concentrically related to the drum and engaged by the pinion on the opposite end of said shaft, a brake for holding said ring gear, means for driving the drum independently of the gearing described and including a gear

surrounding the ring gear but directly connected with the adjacent head of the drum, means for operating the concentric drive pinion, including a gear concentrically related to the opposite head of the drum, a brake for said last mentioned gear and a brake acting directly on the drum.

22. In combination, a supporting shaft, a drum rotatably mounted thereon, a driving pinion rotatably mounted on said shaft at one end of the drum, a ring gear rotatably mounted on said shaft at the opposite end of the drum, a shaft journaled eccentrically in the drum, pinions on the opposite ends of said shaft, one in mesh with the driving pinion and the other in mesh with said ring gear, means for operating the driving pinion, means for releasably holding the ring gear, including a brake ring rotatable with the ring gear, a brake band engageable with said brake ring, a brake acting directly on the drum and means for directly driving the drum independently of the gearing described and including a ring gear attached to the head of the drum at the side of the brake ring.

23. In combination, a supporting shaft, a drum rotatably mounted thereon, a driving pinion rotatably mounted on said shaft at one end of the drum, a ring gear rotatably mounted on said shaft at the opposite end of the drum, a shaft journaled eccentrically in the drum, pinions on the opposite ends of said shaft, one in mesh with the driving pinion and the other in mesh with said ring gear, means for operating the driving pinion, means for releasably holding the ring gear, including a brake ring rotatable with the ring gear, a brake band engageable with said brake ring, a brake acting directly on the drum and means for directly driving the drum independently of the gearing described and including a ring gear attached to the head of the drum at the side of the brake ring, a gear adjacent the opposite head of the drum and directly connected with the driving pinion and a brake ring attached to and adjacent said gear.

24. In hoist mechanism, a supporting shaft, a hoisting drum journaled on said shaft, a sleeve journaled on said shaft at one end of the drum, a pinion on the inner end of said sleeve, a gear on the outer end of said sleeve, a shaft journaled eccentrically in said drum, a pinion on one end of said shaft in mesh with the sleeve pinion, a sleeve journaled on the supporting shaft at the opposite end of the drum, a ring gear carried by said last mentioned sleeve, a pinion on the opposite end of the drum carried shaft in mesh with said ring gear and a gear attached to one head of the drum for directly driving the same.

25. In hoisting mechanism, a drum having end heads, a concentric drive gear connected

- to one end head, a relatively rotatable concentric gear at the opposite end of the drum, a concentric pinion operated by said latter gear, a pinion eccentrically journaled in the 5 drum and driven by said concentric pinion, a ring gear concentrically related to the first mentioned head of the drum and an eccentric pinion driven by said first mentioned eccentric pinion and in mesh with said ring gear 10 and driving gearing for the gear which is connected with the head of the drum.
26. In hoisting mechanism, a drum, means for driving said drum at one speed and means for effecting the drive of said drum at a different speed, including a ring gear concentrically arranged at one end of the drum, a pinion journaled eccentrically in the drum in mesh with said ring gear, a concentrically arranged gear for operating said eccentrically mounted pinion and means for releasably holding the ring gear against rotation and including a frictional brake for holding the ring gear for short periods and a positive lock for securing the ring gear for 25 longer periods.
27. In hoisting mechanism, a drum, means for driving said drum at one speed and means for effecting the drive of said drum at a different speed, including a ring gear concentrically arranged at one end of the drum, a pinion journaled eccentrically in the drum in mesh with said ring gear, a concentrically arranged gear for operating said eccentrically mounted pinion and means for releasably holding the ring gear against rotation and including a stop shiftable into holding relation with respect to the ring gear and a brake operative to hold the ring gear when the stop is withdrawn.
- 40 28. In hoist mechanism, a hoisting drum, gearing for directly rotating the same, gearing for indirectly rotating the drum, including a gear concentrically arranged at one end of the drum, a cat head shaft parallel to 45 the axis of the drum, a gear on said cat head shaft for engagement with said indirect drive gear, means for controlling the drive relation between said indirect drum drive gear and said cat head shaft gear and means 50 for holding the drum against rotation when said cat head drive is effective.
29. In hoist mechanism, a hoisting drum, a high speed drive for said drum, a low speed drive for said drum including a concentrically disposed gear at one end of the drum and rotatable independently of the same, a cat head shaft adjacent said drum, gearing operable at will to drive said cat head shaft from said low speed drum driving gear and 55 means operable at will to hold the drum against rotation or to permit rotation of the same when the cat head shaft is being driven.
- 60 30. A hoisting drum having end heads, concentric drive gears at the outer sides of 65 said end heads, brake rings at the outer sides of said gears, independently operable brake bands for said brake rings, selectively operable gearing in mesh with the gears at the heads of the drum, connections of different speed ratios between said gears and the drum, 70 brake rings on the drum heads at the inner sides of the gears and brake bands operable on said drum head brake rings.
31. In combination, a hoisting drum having end heads, shafting beneath said hoisting drum substantially parallel with the axis of the drum, bevel gears on said shafting oppositely faced and arranged below the drum in line with the space between said end heads, opposed bevel pinions on an axis at right angles to the shafting, disposed between said bevel gears and in mesh therewith and drive gearing below the drum extending from said bevel gears to the drum and including gear connections on the shafting substantially in 75 line with the end heads of the drum.
32. Hoist mechanism comprising in combination a mounting frame, drive means mounted at one end of said frame, a hoisting drum mounted on the frame adjacent said 80 drive means, gearing for operating said drum including drive shafting journaled on the frame and extending from the drive means beneath and beyond the hoisting drum, couplings in the portion of said drive shafting 85 extending beyond the drum, a clutch in the drive shafting between said couplings and controlling operation of the shafting extending beyond the hoisting drum, and said couplings enabling said clutch to be dropped from the drive shafting without disturbing other parts of the hoist.
- In witness whereof, I have hereunto set my hand this 28th day of November, 1925.
